KNOCKDOWN CRATED CARTON

Walter C. George, St. Louis, and Frederick R. Buhrmaster, Webster Groves, Mo., assignors to Gaylord Container Corporation, St. Louis, Mo., a corporation of Maryland

Application October 26, 1940, Serial No. 362,980

5 Claims. (Cl. 217—16)

This invention relates to shipping containers, particularly knockdown crated cartons. It has for its principal objects to devise a simple and inexpensive lightweight shipping container of the above type which can be conveniently shipped in knockdown condition in the form of a compact package and quickly and easily assembled into a crated carton which is strong and rigid, particularly at the corners and edges, and in which the carton material is well protected by the crating. The invention consists in the knockdown crated carton and in the parts and combinations and arrangements of parts hereinafter described and claimed.

In the accompanying drawings, which form part of this specification and wherein like symbols refer to like parts wherever they occur,

Fig. 1 is a top plan view of a knockdown crated carton embodying our invention,

Figs. 2 and 3 are elevations of two adjacent sides of said carton,

Figs. 4 and 5 are vertical sections on the lines 4—4 and 5—5, respectively, in Fig. 1,

Fig. 6 is an enlarged horizontal cross section on the line 6—6 in Fig. 3,

Figs. 7 and 8 are perspective views looking at opposite sides of one of the end closure members or sections of the carton,

Fig. 9 is a perspective view of one of the corner keys of the carton,

Fig. 10 is an edge view of the knocked down body section of the carton,

Fig. 11 is a fragmentary side elevational view, showing a modified arrangement for securing together the corner cleats fixed to the ends of the set-up side wall section of the carton; and

Fig. 12 is a horizontal cross-section on the line 12—12 in Fig. 11.

Our knockdown crated carton comprises a rectangular strip A of corrugated board, fiberboard or like material that is bent along three parallel score lines and its free ends brought together to form the four side walls of the carton. Secured flatwise to the outer face of the strip A along the end margins thereof are corner cleats or slats 1 and 2, respectively. The securing means for the corner cleats 1 and 2 preferably comprises staples 3 that are driven through the strip A from the inner side thereof into said cleats. The cleat 1 extends beyond the end of the strip A and across the outer edge of the cleat 2 and terminates flush with the outer side face of the latter. The outer vertical edge of the cleat 2 has a tongue 4 along the inner corner thereof that fits into a corresponding groove 5 in the adjacent or opposing

inner side face of the cleat 1. The corner cleats may be secured together by gluing the tongue 4 of the cleat 2 in the groove 5 of the cleat 1 and/or by nails 6 that are driven through the cleat 1 into the cleat 2. As shown in the drawings, the cleat 2 terminates flush with the upper and lower edges of the strip A; and the cleat 1 extends above and below said edges of said strip.

Each of the three remaining corners of the carton is stiffened, strengthened and protected by means of upright wooden cleats or slats 7 and 8. The corner cleat 7 is secured flatwise to the outer face of one side wall of the carton with its outer vertical edge spaced from the corner thereof; and the other cleat 8 is secured flatwise to the outer side face of the other side wall of said carton and extends outwardly beyond said first mentioned side wall with its outer vertical edge disposed in flush alignment with the outer side face of the cleat 7. The projecting outer marginal portion of the cleat 8 has a longitudinal groove 9 formed in the inner side face thereof, the inner side wall of this groove being substantially flush with the outer side face of the side wall to which the cleat 7 is secured. The cleat 7 is rabbeted, as at 10, along the inner corner of its outer vertical edge, said rabbet having the same width and depth as the groove 9 and being located directly opposite the latter. As shown in the drawings, the cleat 7 terminates flush with the upper and lower edges of the side wall to which it is secured; and the cleat 8 extends above and below the side wall to which it is secured.

The rabbeted edge of the cleat 7 and the grooved margin of the cleat 8 and the side wall to which the cleat 7 is secured cooperate to form an undercut or T-shaped vertical groove 11 between said cleats adapted to slidably receive a key member in the form of a wooden strip 12 of substantially T-shaped cross section. This key strip has a wide inner portion 13, which bears flatwise against the outer face of the side wall to which the cleat 7 is secured and snugly fits the rabbet 10 of said strip and the groove 9 of the strip 8, and a narrower outer portion 14, which snugly fits the space between said cleats outwardly of said rabbet and groove and has its outer side face disposed flush with the outer side face of the cleat 7 and the outer edge of the cleat 8. The key strip 12 is of the same length as the cleat 7 and terminates flush with the upper and lower ends thereof. The corner cleats 7 and 8 are secured to the corrugated board strip A preferably by means of staples 15 that are driven through said strip from the inner side thereof into said cleats.

By the arrangement described, the corner defined by the free ends of the corrugated board strip A and the cleats 1 and 2 secured thereto is held square by the tongue and groove joint between said cleats, while each of the three remaining corners is held square by the engagement of the key strip 12 with the groove 11 between the corner cleats 1 and 8. At the same time, these corner cleats serve as crating which stiffens, strengthens and protects the weaker carton material.

The carton is provided with duplicate top and bottom closure members B, each comprising a rectangular piece 16 of corrugated board, fiberboard or like material having wooden slats or cleats that are secured flatwise to one face or surface thereof flush with the edges thereof and cooperate to form a rigid edge frame 17 that snugly fits within the rectangular body formed by the corrugated board strip A. If desired, the side walls of the carton may be glued or otherwise secured to the outer edge of the edge frame 17. Secured flatwise to the other face or surface of each corrugated board closure member 16 along two opposite margins thereof are wooden cleats 18 that extend beyond said closure and terminate flush with the ends of the long corner cleats 1 and 8. One of the cleats 18 is disposed with its outer side edge in abutting relation to the inner side faces of the projecting ends of the corner cleats 1 and 8 on one side wall of the carton and with its projecting ends secured to the ends of adjacent corner cleats 2 and 7 and terminating flush with the outer side faces thereof. The other closure cleat 18 is disposed with its outer side edge in abutting relation to the inner side faces of the corner cleats 8 on the opposite side wall of said carton with its projecting ends secured to the ends of adjacent corner cleats 7 and terminating flush with the outer side surfaces thereof. As shown in the drawings, the outer side edges of the cleats 18 extend slightly beyond the edge of the closure so as to seat against the longitudinal edge of the adjacent side wall of the carton. The closure members B are secured in place preferably by means of wood screws 19 which extend through the projecting ends of the cleats 18 and are threaded into the ends of the corner cleats 2 and 7 abutting thereagainst. The edge frame 17 of each end closure 16 is secured thereto preferably by nails 20 that are driven through said frame and end closure into the cleats 18 and thus also secure said cleats to said end closure.

Figs. 11 and 12 illustrate a modified arrangement for connecting the corner cleats together at the ends of the strip A. In this construction, the corner cleat 2a has dowels 4a projecting from the outer vertical edge thereof that fit in holes 5a provided therefor in the adjacent face of the corner cleat 1a. The corner cleats 1a and 2a, like the corner cleats 1 and 2, may be secured together by glue and/or nails 6.

The hereinbefore described knockdown crated carton has several important advantages, the cleats along the top and bottom edges and vertical corners of the carton cooperate to form a crating therefor and thus serve to protect the carton material from injury and also serve to strengthen and stiffen the carton both horizontally and vertically and assist the closure members in preventing the carton from being thrown out of square. The cleated body forming strip A is made of a single piece of corrugated board with only three score lines and, as shown in Fig.

10, said strip, with the corner cleats secured thereto, may be shipped in the flat with adjacent corner strips disposed in the same plane. When the body forming strip is bent along the three score lines to form the rectangular body of the carton, the corner cleats 1 and 8 at each corner thus formed are separated leaving a space therebetween but this space or groove 11 is closed by the locking strip 12 which tends to hold said corner cleats at right angles to each other and the corner square. The corner formed by the two ends of the strip A is held rigid by the connected corner cleats 1 and 2 or 1a and 2a fixed to said ends. The top and bottom closures are strengthened and stiffened by the cleats thereof and are quickly and easily secured in position by securing the projecting ends of the cleats 18 to the ends of adjacent vertical corner cleats, these projecting ends prevent endwise displacement of the key strips 12.

Obviously numerous changes may be made without departing from the invention and we do not wish to be limited to the precise construction shown.

What we claim is:

1. A knockdown crated carton comprising a rectangular body made of a single strip of corrugated board, fiberboard or the like scored along three lines and bent along said lines and its free ends brought together to form said rectangular body, cleats secured to said free ends of said strip and secured together at the corner formed by said ends, two cleats secured flatwise to the outer face of said strip parallel with and adjacent to each of said score lines, one of said two cleats being spaced inwardly from the corner defined by the bend at said score line and the other cleat extending outwardly beyond said corner, and a removable strip interposed between adjacent longitudinal faces of said two cleats and covering the outer face of the portion of the body strip therebetween.

2. A knockdown crated carton comprising a rectangular body made of a single strip of corrugated board, fiberboard or the like scored along three lines and bent along said lines and its free ends brought together to form said rectangular body, cleats secured flatwise to the outer face of said strip at the free ends thereof and having overlapped interfitting portions secured together at the corner formed by said ends, and two cleats secured flatwise to the outer face of said strip parallel with and adjacent to each of said score lines, one of said two cleats having its longitudinal outer side marginal portion disposed outwardly beyond the corner defined by the bend at said score line and the other cleat being disposed with its longitudinal outer side edge spaced inwardly from said longitudinal outer side marginal portion, said longitudinal outwardly disposed outer side marginal portion and said longitudinal inwardly spaced outer side edge being shaped to provide an undercut space therebetween, and a slide strip snugly fitting said undercut space and covering the outer face of the portion of the body strip located opposite said space.

3. A knockdown crated carton comprising a rectangular body made of a single strip of corrugated board, fiberboard or the like scored along three lines and bent along said lines and its free ends brought together to form said rectangular body, cleats secured flatwise to the outer face of said strip at the free ends thereof and secured together at the corner formed by said ends, and two cleats secured flatwise to the outer face of

said strip parallel with and adjacent to each of said score lines, one of said two cleats having its outer side edge disposed outwardly beyond the corner defined by the bend at said score line and the other cleat being disposed with its outer side edge spaced inwardly from said corner and with its outer side face disposed in substantial flush alinement with said outwardly disposed outer side edge of said first mentioned cleat, said inwardly spaced outer side edge of said other cleat and the opposing inner side face of said first mentioned cleat being shaped to provide an undercut space between said two cleats, a slide strip snugly fitting said undercut space with its outer side face in substantial flush alinement with the outer side edge of said first mentioned cleat and the outer side face of said other cleat, and end closures secured to opposite ends of one of said two cleats in abutting relation to the corresponding ends of said slide strip.

4. A knockdown crated carton comprising a rectangular body made of a single strip of corrugated board, fiberboard or the like scored along three lines and bent along said lines and its free ends brought together to form said rectangular body, cleats secured flatwise to the outer face of said strip at the free ends thereof and secured together at the corner formed by said ends, and two cleats secured flatwise to the outer face of said strip parallel with and adjacent to each of said score lines, one of said two cleats having its longitudinal outer side marginal portion disposed outwardly beyond the corner defined by the bend at said score line and the other cleat being disposed with its longitudinal outer side edge spaced from said outer side marginal portion and said

- corner, said longitudinal outer side marginal portion and said longitudinal outer side edge having opposed longitudinal grooves therein, and a slide strip interposed between said longitudinal outer side marginal portion and said longitudinal outer side edge and having its longitudinal edge portions shaped to fit the opposed longitudinal grooves therein.
5. A knockdown crated carton comprising a rectangular body made of a single strip of corrugated board, fiberboard or the like scored along three lines and bent along said lines and its free ends brought together to form said rectangular body, cleats secured flatwise to the outer face of said strip at the free ends thereof and secured together at the corner formed by said ends, and two cleats secured flatwise to the outer face of said strip parallel with and adjacent to each of said score lines, one of said two cleats having its longitudinal outer side marginal portion disposed outwardly beyond the corner defined by the bend at said score line and the other cleat being disposed with its longitudinal outer side edge spaced from said longitudinal outer side marginal portion, said longitudinal outer side marginal portion and said longitudinal outer side edge having opposed longitudinal grooves therein, a slide strip interposed between said outer side marginal portion and said outer side edge and having its longitudinal edge portions shaped to fit the opposed longitudinal grooves therein, and end closures for said carton disposed in abutting relation to opposite ends of said slide strip.
